UNITED STATES PATENT OFFICE.

CARL E. PEARSON, OF CAMDEN, NEW JERSEY, ASSIGNOR TO MOTOR REQUIREMENTS CORPORATION, OF CAMDEN, NEW JERSEY, A CORPORATION OF NEW JERSEY.

GASOLINE PURIFIER.

Application filed May 16, 1927. Serial No. 191,603.

This invention relates to gasoline purifiers for use with internal combustion engines, proposing a construction which is to be interposed in the gasoline feed line and where-
5 in chamois constitutes the filtering element. The object of the invention is a construction which combines the advantages of compactness, ample filtering surfaces, effective deposit of the solid matters and impurities
10 removed by the filtering element, easy accessibility of the enclosed parts, and low manu-
facturing cost.

An embodiment of the invention is illus-
15 trated in the accompanying drawings, in
which:

Figure 1 is a front elevation of the puri-
fier.

Figure 2 is a vertical sectional view.

Figure 3 is a view partly in elevation and
20 partly in vertical section of the filtering ele-
ment.

Figure 4 is a plan view of the purifier and
its supporting means.

Figure 5 is a section on the line 5—5 of
25 Figure 2.

Figure 6 is a plan view of the distribut-
ing ring.

Figure 7 is a view showing the purifier as
applied in use between the fuel tank and
30 the vacuum tank of an automobile.

The purifier includes a closed casing indi-
cated generally at 1 and which is com-
posed of an upper section 2 and a lower
35 section 3, these being secured together by
bolted flange connections 4. The section 2
is cylindrical and is formed with a top plate
5 and the section 3 is substantially cup-
shaped with its bottom preferably rounded.
The casing 1 encloses a filtering unit which
40 consists of an inner screen 6 of chamois
and an outer screen 7 of fine wire mesh
which surrounds and is spaced from the
chamois 6. The screen 6 is in the form of
a continuous sleeve or envelope which is
45 vertically arranged and which is secured
upon an enclosed re-enforcing frame 8 by
which the collapse of the chamois under
suction influence is avoided. The upper
portion of the chamois sleeve 6, being that
50 portion which lies within the casing section
2 is preferably cylindrical and the lower

portion of said sleeve, being that portion
which lies within the casing section 3 is
preferably frusto-conical, the re-enforcing
frame 8 being shaped to conform. The
55 screen 7 surrounds the frusto-conical part
of the chamois sleeve 6 and at its upper end
is attached to a cylindrical baffle 9 which
surrounds the cylindrical part of the chamois
sleeve and is suitably spaced from
60 the same. The casing section 2 is formed
at one side with an inlet nipple 10 and the
baffle 9 carries a distributing ring 11 which
is inclined downward from a point adjacent
the lower side of said inlet nipple and
65 which extends across the space between the
baffle and the wall of the casing section 2
as shown in Figure 2, the ring 11, the
baffle and the casing section 2 providing an
annular inlet chamber 12. The upper mar-
70 ginal portions of the baffle 9, the sleeve 6
and the frame 8 fit within a ring 13 of
channel cross section which is centered by
an annular shoulder 14 extending between
the cylindrical wall of the casing 2 and the
75 top plate 5. At its lower end the filtering
unit is provided with a head 15 having an
annular shoulder 16 which fits within the
lower end of the chamois sleeve and the
frame 8 and centers the same. The head 15
80 has a part which projects below said sleeve
and frame as a support and to which the
lower marginal portion of the screen 7 is
suitably secured.

The unit as a whole is supported within
85 the casing 1 by a hollow central stem 17,
the lower end of which has threaded en-
gagement in a central opening of the head
15 and carries a nut 18 and the upper end
90 of which projects through an opening in the
top plate 5 and carries a securing nut 19.
By means of the nut 19 the stem 17 is uti-
lized to hold the filtering unit with its up-
per end, as provided by the ring 13, in air
95 sealed engagement with the top plate 5. The
stem 17 provides an outlet conduit for
the filtered gasoline and is formed near its
upper end with openings 20 through which
the gasoline flows from the interior of the
chamois sleeve.

100 The casing section 3 is provided at its bot-
tom with a drain opening which is normally

closed by a plug 21. This plug projects into the lower end of the stem 17 and also closes openings 22 formed at the lower end of said stem and through which any impurities accumulating on the head 15 may be flushed upon the removal of the plug 20.

The distributing plate 11 is formed with slots 23 arranged in a circle throughout the extent of said plate. In order that the flow 10 of gasoline through the plate may be equalized at points remoter from the inlet nipple 10 with the flow at points nearer said inlet nipple the slots 23 are made of gradually increasing length as shown in Figure 6 toward the side of the plate 11 which is remote from the inlet nipple 10.

The filter may be supported by a suitable bracket 24 from the top of the vacuum tank V.

20 Referring to Figure 7, A is the pipe which leads from the gasoline tank to the inlet nipple 10, B is the pipe which leads from the outlet conduit of the filter, that is to say, the stem 17, to the vacuum tank and 25 C is the pipe which leads from the vacuum tank to the motor.

The function of the baffle 9 is to prevent the gasoline as it enters the casing 1 from directly impinging upon the filtering areas 30 and to cause the gasoline to flow downward before it has access to the filter areas. As a result of such downward flow momentum is given to the solid particles which facilitates their deposit in the space or pocket 25 35 of the casing section 3 below the filtering unit. The provision of the baffle 9, however, does not necessitate any reduction in the effective area of the chamois sleeve 6. As soon as the gasoline passes below the baffle 40 9 the entire surface of said chamois sleeve is accessible, the part thereof which lies within the baffle as well as the part which lies below the baffle. Thus the chamois sleeve is substantially completely submerged in the 45 gasoline and a relatively large filtering area is presented which at all points of its extent is uniformly subject to the suction influence, while the space below the filtering and screening unit is sufficiently large to provide 50 for the accumulation of any water that may be carried over into the gasoline without the danger of such water being carried through the chamois sleeve. The suction influence being uniformly distributed over the 55 whole of the relatively large area of the chamois sleeve it follows that such influence at any single point of the sleeve is relatively small so as to minimize interference with the descent of the heavier solid particles to 60 the bottom of the casing.

Having fully described my invention, I claim:

1. In a gasoline purifier, a casing, a filtering element therein including a chamois sleeve of annular horizontal section, a ver-

tical annular baffle surrounding and spaced from the upper portion of the sleeve, the casing having an inlet adjacent said baffle, an outlet leading from the interior of the sleeve, and a perforated distributing ring arranged below the inlet and extending across the space between the baffle and the casing, the perforations of said ring increasing in area away from said inlet.

2. In a gasoline purifier, a casing, a filtering element therein including a frame, a chamois sleeve of annular horizontal section fitted upon said frame, a supporting head at the lower end of said frame, a hollow stem extending through the interior of said sleeve 80 with its lower end connected to said head and its upper end projecting through the top of the casing, a nut on the projecting upper end of said stem to support the same and hold the filtering unit with its upper end 85 lying against the upper end of the casing, the stem serving as an outlet conduit and having openings through which the gasoline may flow from the interior of the casing, and a gasoline inlet nipple formed in a wall 90 of the casing.

3. In a gasoline purifier, a casing, a filtering element therein including a frame, a chamois sleeve of annular cross section fitted upon the frame, a lower head supporting the frame, a hollow stem extending through the head, the sleeve and the casing, said stem serving as an outlet conduit and communicating with the interior of the sleeve by upper openings and lower openings, a gasoline inlet nipple formed in a wall of the casing, and a drain plug fitted into the lower end of the casing and extending into said stem normally to close the lower openings.

4. In a gasoline purifier, a casing having a gasoline inlet nipple, a filtering unit within the casing including a filtering element of annular horizontal section, a closure for the lower end of said element, an annular baffle adjacent said nipple and in spaced surrounding relation to the upper portion of said element, an outlet conduit leading from the interior of said element, said conduit being secured to said closure and means for securely holding said element in sealed engagement with the top of the casing.

5. In a gasoline purifier, a casing having a gasoline inlet nipple, a filtering unit within the casing including a filtering element of annular horizontal section and an annular baffle adjacent said nipple and in spaced surrounding relation to the upper portion of said element, an inclined perforated distributing ring below said nipple and extending across the space between said baffle and said casing, and an outlet conduit leading from the interior of said element, the perforations of said ring increasing in area away from said inlet.

6. In a gasoline purifier, a casing having

an upper and lower part removably secured together, an inlet nipple leading to said upper part, a filtering element of substantially circular cross section in said upper part and formed with converging sides in said lower part, a baffle in said upper part interposed between said inlet nipple and

said filtering element and an outlet conduit extending through said casing and filtering element and communicating with the interior of said element. 10

In testimony whereof I hereby affix my signature.

CARL E. PEARSON.
